Application October 12, 1950, Serial No. 189,865

7 Claims. (Cl. 155—196)

2

Fig. 3 is a top plan view thereof with the cardboard casing removed.

Fig. 4 is a section view thereof taken on lines 4—4 of Fig. 3 in the direction of the arrows.

5 Fig. 5 is a section view thereof taken on lines 5—5 of Fig. 3 in the direction of the arrows.

Fig. 6 is a perspective view of a modified form of the invention with the slip cover removed, and having an arm rest.

10 Fig. 7 is a section view thereof taken on lines 7—7 of Fig. 8 in the direction of the arrows.

Fig. 8 is a section view thereof taken on lines 8—8 of Fig. 7 in the direction of the arrows.

15 Fig. 9 is a perspective view of one of the substantially L-shaped bracing members.

In the drawings, the invention is shown generally at 10 in Fig. 1. The fabric slip cover 11 having the cushioned seat 12, completely covers the casing (see Fig. 2). This casing is formed of relatively thin material such as cardboard or fiber board. It preferably but not necessarily includes the box-like bottom 13 and the side, end, seat, forward and rear back sections 14, 15, 16, 17 and 18 respectively. Scotch tape 19 or other suitable securing means may be used to connect the several sections. 20 Staples 20 or the like may also be used for such purposes, and in order to secure the bottom to the side and end sections. If desired, it is of course possible to form more than one of the sections from a single blank, as for example the side and rearward back sections. The blank 25 is scored after being stamped to facilitate proper folding.

A plurality of substantially L-shaped panel members 21 having the laterally extending ends 22 are fabricated of cardboard or the like, their contour approximating that of the seat and back of a conventional chair, and when 30 properly set up are disposed in spaced, parallel relation. Four of such members are shown in the drawings (see Fig. 3), although the number employed is a matter of choice. Each panel has a plurality of longitudinally spaced, vertically disposed slots 23 formed in the seat portion thereof, the slots extending from a point in proximity to the vertical center of said seat portions upwardly through the edges thereof.

The back portions of each panel have substantially horizontally disposed slots 24 formed therein in vertical, spaced relation. Three of these slots are shown in the drawings (see Fig. 5) although the exact number is not critical and may be varied as desired. Each slot extends from a point in proximity to the horizontal center of its back portion rearwardly through the edge thereof.

45 50 For purposes hereafter described, each of the panels is provided with a slot 25 disposed rearwardly and downwardly from the vertex 26 forming the juncture of said seat and back portions.

Cooperating with the L-shaped panel members are 55 bracing struts 27, one being provided for each of the slots 23 in the seat portion thereof. Some of these cross struts may have their ends laterally extended or deflected as at 28. Each strut is provided with a series of spaced parallel slots 28a extending inwardly or upwardly from the lower edges thereof to approximately the vertical center thereof. The slots 28a are spaced apart such distances as it is desired that the L-shaped panels are to be maintained, and the slots 23—28a interengage with each other in such manner as to tightly lock the panels and struts in interlocked relationship. The depth of the slots 60 65 70 75 80 85 90 95 98 99 100 101 102 103 104 105 106 107 108 109 110 111 112 113 114 115 116 117 118 119 120 121 122 123 124 125 126 127 128 129 130 131 132 133 134 135 136 while the lower edges of the said cross struts will terminate adjacent to the bottom plane of the said L-shaped members. In order to further reenforce and lend rigidity to the construction, the two most remote transverse strut portions may be formed of one blank, being the upturned ends 29 of the base portion 30 to constitute a bottom upon which the remaining cross struts 27 rest. The rear upturned end 29 is slotted inwardly from its upper end to interengage with slots 25 near the rear ends of the L-shaped panels.

Extending approximately at right angles to the back portions of said L-shaped members are the bracing struts or cross pieces 38'. They also have slots 39' formed therein, as described in connection with the transverse elements, so that they may be disposed in interlocking relation with the slots of said back portion. (See Fig. 4.)

After the transverse struts are interlocked with said L-shaped members, the chair contour desired is thereby formed. Next the side, bottom end and back sections are disposed thereabout in embracing, enveloping relation thus forming a casing or shell for the assembled pieces (see Fig. 2.)

While a chair construction thus described may be formed, it is also possible to provide for the modification shown in Figs. 6, 7 and 8. This modification is designed as a part of a sectional piece of furniture, the illustration picturing the lefthand unit (facing from the chair) having the arm rest shown generally at 31. The arm rest comprises preferably a casing 32 formed from one blank which is scored along vertical planes and then folded into substantially rectangular form as shown in Fig. 8. There are vertically disposed slots 33 formed in the lower side wall positions of the casing so that it may be interlocked with the transverse struts in a manner as heretofore described. The casing is positioned between adjacent L-shaped members. Interposed between the cross struts and the side walls of the casing are the interlocked upright members 34. A cover 35 may be provided to enclose the construction.

While the invention has been illustrated and described in great detail in the drawings and foregoing description, the same is to be considered as illustrative and not restrictive in character.

The invention claimed is:

1. A chair construction formed of stiff sheet material, comprising a plurality of substantially L-shaped panels arranged in spaced substantially parallel relation, the bases and arms of each of said panels forming seat and back portions respectively, the bases of said panels having a plurality of spaced substantially vertical notches formed therein, said notches extending from a point adjacent the vertical center of said bases upwardly through the edges thereof, the respective notches of each base being in alignment with the corresponding notches of adjacent bases, the arms of said panels having a plurality of substantially horizontal spaced notches formed therein, said notches extending from a point adjacent the horizontal center of said arms rearwardly through the edges thereof, the respective notches of each arm being in alignment with the corresponding notches of adjacent arms, a series of transverse bracing struts having a plurality of similarly spaced notches disposed laterally therein and slidably interfitting with the corresponding notches in said seat and back portions, said transverse struts being associated with said panels in substantially right angular interlocking relation, and a casing enclosing said panels and struts in confining engagement therewith to provide a seat and back rest.

2. A chair construction formed of stiff sheet material, comprising a plurality of substantially L-shaped panels arranged in spaced substantially parallel relation to form the chair contour, the bases and arms of said panels constituting respectively the seat and back portion of the chair, a plurality of transverse bracing struts angularly disposed relative to said panels, said panels and said

struts each having a plurality of spaced aligned cooperating notches formed therein to permit an interlocking association therebetween, an arm rest for said chair comprising a casing having a substantially rectangular wall provided with cooperating notches extending inwardly from the lower end thereof, said wall being nested between said panels with its said slots in interlocking relation with said transverse bracing struts, a plurality of bracing struts abutting the inside surfaces of said casing, and a cover enclosing said struts and panels in confining engagement therewith to provide a seat and back rest.

3. An article of furniture comprising a supporting structure having a plurality of similar panels of thin material each comprising a seat portion and an integral offset back portion, said seat and back portions each having a plurality of parallel slots extending inwardly a predetermined distance from one edge thereof, reenforcing struts each having parallel slots extending inwardly a predetermined distance from one edge thereof, said reenforcing struts having the edges of the slots thereof interlocking engaged with the edges of the slots of said seat and back portions, the said struts holding the said panels in parallel spaced relation with the corresponding edges of the seat portion in the same planes and the front and back edges of the back portions in the same planes, the edges of said struts disposed in the same planes with their respective seat and back portion edges, and a covering enclosing said panels and struts and engaging the edges thereof.

30 4. An article of furniture comprising a supporting structure having a plurality of similar panels of thin material each comprising a seat portion and an offset back portion, said seat and back portions each having a plurality of spaced slots extending inwardly predetermined distances from the top and back edges thereof respectively, bracing struts of similar material each having spaced slots extending inwardly from one edge and of depths corresponding to the depths of said panel slots, said bracing struts disposed transversely of said panels with the slot edges of the panels and struts embracing the material of the panels and struts beyond the bottoms of their respective slots whereby the panels and struts maintain one another in spaced relation with the opposing edges of the seat portions in the same respective planes and the front and back edges of the back portions in the same respective planes with the corresponding edges of the bracing struts in the same planes with their respective seat and back portion edges, and a covering enclosing said panels and bracing struts.

50 5. An article of furniture comprising a supporting structure having a plurality of similar panels of thin material each comprising a seat portion and an offset back portion, said seat and back portions each having a plurality of spaced slots extending inwardly predetermined distances from the top and back edges thereof respectively, bracing struts of similar material disposed transversely of said panels and each having spaced slots extending inwardly from an edge thereof, the slots of said panels and struts so located and of such depth and breadth as to permit said panels and struts to interengage with one another with the material of said struts and panels beyond the bottoms of said slots embraced by the edges of said slots with the edges of said panels and struts in the same planes, and a covering of thin relatively stiff sheet material enclosing said panels and bracing struts.

60 6. An article of furniture comprising a supporting structure having a plurality of spaced laterally disposed supporting struts formed of thin sheet material, an arm rest comprising a sheet of thin relatively stiff material bent upon itself to form a four-walled rectangular casing provided in one wall thereof with inwardly directed slots spaced apart a distance corresponding to the distance between said struts, the edges of said slots embracing said struts in interlocking engagement, and reenforcing mem-

bers of thin relatively stiff sheet material disposed within said casing in upright relationship and extending from the bottom to the top thereof.

7. An article of furniture comprising a supporting structure having a plurality of similar seat panels of thin material each provided with a plurality of parallel slots extending inwardly a predetermined distance from one edge thereof, reenforcing struts formed of thin relatively stiff sheet material each having parallel slots extending a predetermined distance from one edge inwardly thereof, said struts having the edges of the slots thereof interlockingly engaged with the edges of the slots of said panels, the said struts holding said panels in spaced parallel relation with the corresponding edges of the seat portion in the same planes with the corresponding edges of the struts, the ends of the struts projecting beyond the end seat panels, an arm rest formed of thin relatively stiff sheet material bent upon itself to form a rectangular casing and provided in a wall thereof with slots extending inwardly from its lower edges and spaced apart distances 20

corresponding to the distances between said struts, said arm rest slots embracing said struts in interlocking engagement, and reenforcing upright members of thin material disposed within said arm rest casing and extending from the bottom to the top thereof.
